US00D756706S

(12) **United States Design Patent**
Kushner

(10) **Patent No.:** **US D756,706 S**
(45) **Date of Patent:** **** May 24, 2016**

(54) **GLASS BUBBLE PINT GLASS**

(71) Applicant: **Robert Kushner**, Pok Fu Lam (HK)
(72) Inventor: **Robert Kushner**, Pok Fu Lam (HK)
(73) Assignee: **Urban Trend LLC**, Newport Beach, CA (US)
(**) Term: **14 Years**
(21) Appl. No.: **29/474,723**
(22) Filed: **Jan. 20, 2015**
(51) LOC (10) Cl. **07-01**
(52) U.S. Cl. **USPC D7/523; D7/509**
(58) **Field of Classification Search**
